UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

CAR-COUPLER-POSITIONING DEVICE.

Application filed June 16, 1926. Serial No. 116,406.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently bent or broken when the couplers are not

within coupling range. Such devices also reduce the number of accidents to trainmen as they are not required to go between the cars and position the coupler preparatory to coupling.

A common form of car coupler positioning device comprises a coupler carrier swingably suspended by links from some part of the car so that the objects and advantages mentioned above are obtained and my invention is an improvement upon such devices and consists in providing a shiftable bearing construction to increase the eccentricity of the weight of the coupler (and its associated parts) about its point of support, thus increasing the resultant force tending to return the coupler to the longitudinal center of the car (or away therefrom when the car is tipped). I accomplish this result without necessarily increasing the vertical rise of the coupler. This is important because the A. R. A. standard dimensions only permit 3/4" vertical rise of the coupler.

In my device the coupler carrier is swingably suspended from any convenient part of the car by a link at each of its ends and is provided with means, such as lugs, to prevent lateral movement of the coupler relative thereto. These links have a pivot which entirely supports the carrier through a predetermined amount of swinging movement of the links and also when the coupler is in its normal central position. At least one of these links has a portion which has unrestricted movement or action during such predetermined movement, but which engages the car part (or carrier if at the lower end) upon any additional swinging movement in one direction, and causes its pivot to move away from its bearing so that the load on this link is shifted entirely to the said portion. The link may be provided with spaced apart portions on the opposite sides of the link so that a similar action takes place when the carrier moves in the opposite direction, or oppositely projecting portions may be used on the separate links to accomplish the same purpose. In practice the "predetermined movement" of the link would permit the carrier and coupler to move laterally during the ordinary running motions of the car.

The shiftable bearing construction may be used on one or both ends of one or both links. It may be used to function on one link when the carrier moves in one direction, and upon

the other link when the carrier moves in the other direction. Furthermore, the shiftable bearing construction may be arranged with contacting points or lines between the link and car part or between the link and the carrier but a journalized bearing is preferable to provide greater bearing area, at least during the predetermined movement. In a journalized arrangement, the journal may be on the car part and the journal bearing on the link (as shown in Fig. 10) or vice versa (as shown in Fig. 4) or in fact the link may have a journal and a journal bearing engaging a journal bearing and journal, respectively, on the car part (as shown in Fig. 10).

In the drawings:

Fig. 1 shows a typical application of my device to a railway car.

Fig. 2 is a section on line 2—2 of Fig. 1.
20 Fig. 3 is a side elevation of Fig. 1.

Figs. 4, 5 and 6 are skeleton diagrams showing the device, respectively, in normal position, at the end of the predetermined movement and upon additional movement.

25 Fig. 7 is a detail of the carrier.

Fig. 8 is a detail of the link.

Fig. 9 is a detail of a modified link.

Figs. 10 and 11 are skeleton diagrams showing a modified form of the device, respectively, in normal position and upon movement in excess of the predetermined movement.

Fig. 12 is a detail of the link of the modified form.

35 In the arrangement shown in Figs. 1 to 8 the double bearing and pivot construction is used at the upper ends of the links and the lower ends of the links are pivoted to the carrier 1. When the coupler 2 is in its normal (central) position, the link 3 is entirely supported by its pivot 4, which pivot also supports the link through a predetermined amount of swinging movement, which would permit the coupler to move laterally 40 sufficiently to accommodate the ordinary movements of the train.

The lower end of the link 3 is pivoted to the carrier by the trunnion 5 but any convenient pivot arrangement may be used. 50 The upper end of the link is provided with spaced apart portions 6—7 which have unrestricted freedom of movement or action during such predetermined movement. When the link swings laterally any additional amount in either direction, one of these said portions engages a part of the striking casting (or other car part) and causes the pivot to be raised from its bearing, thus shifting the load on the link entirely to the said portion.

55 This shifting of the bearing moves the center of the effective radius "E" of the link and the parts may be so proportioned as to maintain the same radius or to increase or decrease it as desired. In any event, how-

ever, the eccentricity of the load about its support is increased. Decreasing the effective radius increases the vertical rise of the carrier in a given amount of lateral movement, while increasing the effective radius 70 decreases the said rise.

In the construction illustrated, the effective radius "E" or "F" during the predetermined amount of swing is shorter than the effective radius thereafter (J or H). 75

The eccentricity or lever arm of the load on the link is the horizontal distance between a vertical plane 10 passing through the pivot connection between the link and the carrier, and another vertical plane 11 80 passing through the contacting line of the link with the car part supporting it. The eccentricity "G" of the load at the ends of the predetermined movement is equal to the lateral movement "A" of the carrier, while "C" shows the eccentricity when the link has swung beyond the predetermined amount and the carrier has moved distance "B". There is no eccentricity when the device is in normal position because a vertical 85 plane 12 passing through the upper pivot 4 also passes through the lower pivot 5.

Figs. 7 and 8 show the carrier 1 and link 3, respectively, in detail. The link (of the construction illustrated) has a trunnion pivot 5 at its lower end and another trunnion pivot 4 at its upper end which are connected by a shank 13. The link may have a perforation 14 for a pin, as shown in Fig. 9. The upper end also has spaced apart portions 6 and 7. The shiftable bearing construction may be accomplished by the use of a hook, as shown in Fig. 12.

Fig. 4 shows the device in normal position and Fig. 5 shows the device when the coupler has moved laterally a predetermined amount (A) and Fig. 6 shows the device with the carrier moved an amount (B) greater than the predetermined movement. In these figures the immaterial parts of the car have been omitted.

Figs. 10 and 11 show a modification wherein the double bearing construction is used on both ends of both links. The action is similar to that heretofore described.

The effective radius of the link is affected in a similar manner to that heretofore described. When the coupler and carrier are in normal position and also during the predetermined movement of the link the portion 20 of the carrier 1 pivots upon the portion 22 of the link and the link is entirely supported by the pivoted portion 23 of the car part 24, and the portions 25 and 26 have unrestricted movement or action 120 during such predetermined movement. Upon any additional movement of the carrier, for instance, toward the right, as shown in Fig. 11, the upper part of the link moves away from the portion 23 of the car part 125 130

and the load is entirely shifted to the portion 27 of the car part 23. At the same time the portion 22 of the link moves away from the carrier so that the load of the carrier upon the link is entirely shifted to portion 26 of the link. The opposite shifting of bearings takes place when the carrier moves to the left.

When the carrier moves laterally (say 10 distance "K") the eccentricity (L or M) of the load is the horizontal distance between vertical planes, one of which (30) passes through the contact line of the car part and the link and the other of which (31) passes 15 through the contact line of the link and the carrier. There is no eccentricity when the device is in normal position because a vertical plane passes through the contacting line between the link and the car part and 20 also passes through the contacting line between the link and the carrier. Fig. 12 shows the link of the modified form in detail.

There are certain advantages to be obtained by arranging the spaced apart portions of the link so that both of them support the link when it is in normal position. Such a construction is covered by application for patent Serial No. 116,408, filed 25 June 16, 1926. Other features are disclosed and claimed in that application.

In the device covered by this application the load is shifted from one bearing to another by the lateral movement of the carrier. There are certain advantages in having this shifting performed gradually, which is covered by application for patent 35 Serial No. 116,407, filed June 16, 1926.

The drawings illustrate the preferred 40 form of the invention, though it is to be understood that the invention is not limited to the exact details of construction shown and described, as it is obvious that various modifications thereof within the scope of the 45 claims will occur to persons skilled in the art.

I claim:

1. In a railway car; the combination of a car part element, a coupler carrier element, 50 and a pair of links swingably suspending the opposite ends of the carrier thereto, each link having a pivot entirely supporting one end of the carrier through a predetermined amount of swinging movement, one of said 55 links having a portion with unrestricted action through said predetermined movement which engages one of said elements and entirely supports that end of the carrier through any additional swinging movement 60 in one direction.

2. In a railway car; the combination of a car part element, a coupler carrier element, and a pair of links swingably suspending the opposite ends of the carrier thereto, each 65 link having a pivot entirely supporting one

end of the carrier through a predetermined amount of swinging movement, one of said links having a portion with unrestricted action through said predetermined movement which engages one of said elements and entirely supports that end of the carrier through any additional swinging movement 70 in one direction whereby the effective radius of the link is altered.

3. In a railway car; the combination of 75 a car part element, a coupler carrier element, and a pair of links swingably suspending the opposite ends of the carrier thereto, each link having a pivot entirely supporting one end of the carrier through a predetermined amount of swinging movement, one of said links having a portion with unrestricted action through said predetermined movement which engages one of said elements and entirely supports that end 80 of the carrier through any additional swinging movement in one direction whereby the effective radius of the link is increased.

4. In a railway car; the combination of 85 a car part element, a coupler carrier element, and a pair of links swingably suspending the opposite ends of the carrier thereto, each link having a pivot entirely supporting one end of the carrier through a predetermined amount of swinging movement, one of said links having spaced apart 90 portions with unrestricted action through said predetermined movement, one of which engages one of said elements and entirely supports that end of the carrier through any additional swinging movement in one direction, and the other of which portions 95 engages a part of the same element and entirely supports the same end of the carrier through any additional swinging movement 100 whereby the effective radius of the link is altered by additional swinging movement of the carrier in either direction.

5. In a railway car; the combination of a car part, a coupler carrier, and a pair of links swingably suspending the opposite ends of the carrier thereto, each link having a pivot entirely supporting one end of the carrier through a predetermined amount of swinging movement, one of said links having 110 spaced apart portions at each end with unrestricted action through said predetermined movement, some of said portions engaging the car part and carrier, respectively, and entirely supporting that end of the carrier through any additional swinging movement 115 in one direction, and other of said portions engaging the car part and carrier, respectively, and entirely supporting the same end of the carrier through any additional swinging movement in the opposite direction.

6. In a railway car; the combination of a car part element, a coupler carrier element, and a pair of links swingably sus- 120

125

130

pending the opposite ends of the carrier thereto, each link having a pivot entirely supporting one end of the carrier through a predetermined amount of swinging movement, each of said links having a portion with unrestricted action through said predetermined movement, said portion of one of the links engaging one of said elements and entirely supporting that end of the carrier through any additional swinging movement in one direction and the said portion of the other of the links engaging one of said elements and entirely supporting the other end of the carrier through any additional swinging movement in the other direction.

7. A link for a car coupler positioning device comprising a shank with a pair of oppositely disposed trunnions at each end, and a pair of oppositely disposed projections at one end of the link which extend normal to the trunnions.

8. In a railway car; the combination of a car part element, a coupler carrier element, and a pair of links swingably suspending the opposite ends of the carrier thereto, one of said links having an inwardly projecting hook at one end thereof, the end of the hook forming a journal engageable with a bearing in one of said elements, the end of said hook being out of contact with its bearing when the device is in its normal central position.

9. In a railway car; the combination of a car part element, a coupler carrier element, and a pair of links swingably suspending the opposite ends of the carrier thereto, one of said links having an inwardly projecting hook at one end thereof, the end of the hook forming a journal engageable with a bearing in one of said elements, the inside of said hook forming a bearing engageable with a bearing in one of said elements, the end of said hook being out of contact with its bearing when the device is in its normal central position.

10. In a railway car; the combination of a car part element, a coupler carrier element, and a pair of links swingably suspending the opposite ends of the carrier thereto, said links having an inwardly projecting hook at each end thereof, the ends of the hooks forming journals engageable with bearings in the car part and carrier respectively, the ends of said hooks being out of contact with their respective bearings when the device is in its normal central position.

11. In a railway car; the combination of a car part element, a coupler carrier element, and a pair of links swingably sus-

pending the opposite ends of the carrier thereto, said links having an inwardly projecting hook at each end thereof, the ends of the hooks forming journals engageable with bearings in the car part and carrier respectively, the inside of said hooks forming bearings engageable with bearings in the car part and carrier respectively, the ends of said hooks being out of contact with their respective bearings when the device is in its normal central position.

12. In a railway car; the combination of a car part having an aperture with a bearing on each side of said aperture and an elevated shelf on each side of each bearing, and a swingable link having a trunnion engaging the bearings on opposite sides of the aperture, said link also having spaced apart portions with unrestricted action through a predetermined swing of said link which engages one of said shelves and entirely supports the link through any additional swing of the link.

13. In a railway car; the combination of a car part having an aperture with a bearing on each side of said aperture and an elevated shelf on one side of each bearing, and a swingable link having a trunnion engaging the bearings on opposite sides of the aperture, said link also having a portion with unrestricted action through a predetermined swing of said link which engages one of said shelves and entirely supports the link through any additional swing of the link.

14. In a railway car; the combination of a car element having bearings and other portions, and a swingable link having a trunnion engaging said bearings on said element forming the sole engagement therebetween through a predetermined swing of the link, said link provided with parts which engage said other portions of the element forming the sole engagement therebetween through any additional swing of the link.

15. In a railway car; the combination of a car part, a coupler carrier, and a pair of links swingably suspending the opposite ends of the carrier thereto, one of the links having an inwardly projecting lateral extension with spaced apart supports for the carrier so positioned that the carrier rests entirely upon one support when the link swings in one direction and entirely upon the other support after the link swings a predetermined amount in the other direction, the carrier being out of contact with one of the supports when the device is in normal central position.

ARTHUR E. SMALL.
